(57) **CLAIM**

The ornamental design for a faucet, as shown and described.

DESCRIPTION

FIG. 1 is a perspective view of a faucet showing the new design according to one embodiment.

FIG. 2 is a front view of the faucet of FIG. 1.

FIG. 3 is a rear view of the faucet of FIG. 1.

FIG. 4 is a side view of the faucet of FIG. 1.

FIG. 5 is an opposite side view of the faucet of FIG. 1.

FIG. 6 is a top view of the faucet of FIG. 1; and,

FIG. 7 is a bottom view of the faucet of FIG. 1.

The broken lines in the drawings depict environmental subject matter only and form no part of the claimed design.
